WELL DERRICK SUBSTRUCTURE

John D. McEwen, Pasadena, Calif., assignor, by
mesne assignments, to The International
Derrick & Equipment Company, Columbus,
Ohio, a corporation of Ohio

Application August 20, 1941, Serial No. 407,573

4 Claims. (Cl. 189—21)

This invention relates generally to well drilling equipment and is more particularly directed to improvements in the construction of derricks employed in the drilling of wells.

In most instances when wells are to be drilled, derricks are first constructed over the locations for the wells and these derricks include foundation members which are usually of concrete or other suitable material having the requisite strength and wear-resisting qualities. Upon the foundation, a four-sided pyramidal derrick structure is erected, usually from timbers or structural steel beams and angles. At the lower end of the derrick and over the foundation, a substructure is provided for supporting the floor and the mechanism used in drilling the well. The actual drilling mechanism may be of various types, each of which possesses considerable weight and imposes a great load on the substructure when the well casing is suspended therefrom.

Also, in the drilling operations, large quantities of drill pipe are employed, this being stored within the derrick, until used, by being placed on end on the derrick floor and extended upwardly into the derrick. After the well has been "brought in," part of the mechanism is removed and pumping apparatus, which is comparatively light in weight, is provided in place thereof. It is necessary at the time the substructure is built to make the same sufficiently strong to support the great weight of the drilling apparatus, but when the relatively lighter weight pumping mechanism is substituted for the other apparatus, the substructure has many times the strength needed.

It is, therefore, the primary object of the present invention to provide a substructure having a plurality of independent parts, all of which may be constructed with the requisite strength to perform their intended functions and certain of which may be removed and transferred to the location of new wells upon the completion of the drilling operation.

It is also an object of the invention to provide a derrick substructure formed from a plurality of structural beams and girders upon which the derrick floor and other well-drilling and activating mechanisms may be supported, the portions of the substructure provided for the reception of the drilling apparatus and casing holding means being constructed from members having strength in proportion to the weight of the drilling apparatus and the loads incident to the operation of such apparatus, the latter portions of the sub-

structure being relatively independent from the balance thereof in order that it may be readily removed at the time the drilling table is removed, that is, after the drilling operation has been completed.

A further object resides in providing novel reinforced pedestal means for carrying the relatively heavy girders which furnish the support for the rotary table or other drilling mechanism 10 and the well casing, the girder supporting means providing for the transmission of vibratory forces, created during the drilling operation, directly to the foundation without requiring such forces to pass through the derrick legs and into the 15 footings provided at the lower ends thereof.

Other objects will be apparent from the following description and the accompanying drawings in which a substructure embodying the features of the present invention has been illustrated in detail.

In the drawings:

Fig. 1 is a plan view of the substructure forming the present invention;

Fig. 2 is a vertical transverse sectional view 25 taken on the plane indicated by the line II—II of Fig. 1;

Fig. 3 is a vertical longitudinal sectional view taken on the plane indicated by the line III—III of Fig. 1;

Fig. 4 is a side elevational view looking in the direction indicated by the arrow IV in Fig. 1;

Fig. 5 is a front elevational view of the substructure;

Fig. 6 is a plan view of the substructure after 35 the casing support has been removed therefrom;

Fig. 7 is a front elevational view of a modified form of casing support;

Fig. 8 is a side elevational view of the form 40 of casing support shown in Fig. 7.

Referring more particularly to the drawings, the numeral 1 designates the substructure in its entirety. This substructure is mounted on a concrete foundation including a plurality of blocks 2 provided on the ground adjacent the location 45 for the well bore. The foundation also includes a plurality of relatively large piers 3 which are arranged at the corners of the substructure and are formed for the reception of the corner legs of the derrick. The substructure is substantially 50 square when viewed in plan but, for purposes of description, the axis running vertically in Fig. 1 will be termed the length of the substructure; the transverse axis being termed the width.

Adjacent the center of the substructure, a plurality of relatively large concrete blocks 4 are

provided for the reception of casing supporting mechanism to be hereinafter described. The sub-structure generally includes a plurality of longitudinally extending beams 5 and a second group of beams 6 located beneath the beams 5 and serving as a support for the latter beams. The beams 6 are held in an elevated position above the foundation by a plurality of columns 7 which, in this instance, are formed from structural members having angular cross section. The lower ends of the columns are provided with foundation engaging plates 8 through which securing elements 9 pass to hold the plates and the columns rigidly in place on the foundation. Diagonal braces 10 extend between certain of the columns and serve to reenforce the columns and prevent lateral movement at the upper ends thereof.

Adjacent the central portion of the longitudinally extending beams 5, the transversely extending lower beams include relatively short sections 11 and 12 and terminate in spaced relation from the longitudinal axis of the substructure designated by the line X—X on Fig. 1. The beams 12 are composed of structural members having greater strength than the beam sections 11 and serve to strengthen the derrick floor in their location, the floor at this point receiving the drill pipe stored in the derrick prior to being used in the operation of drilling the well. A large quantity of drill pipe is generally used and therefore the sections 12 must be of great strength to withstand the concentrated load.

The edges of the substructure are provided with channel members 13 which terminate in spaced relation from the corners to receive and be joined with the corner legs 14 of the derrick, said legs being secured at their lower ends to footing members 15 fastened in any suitable manner to the piers 3. Brace bars 16 extend from the footing members 15 to the channel members and serve to strengthen the same and prevent relative movement during the operation of the derrick. Sill members 17 are provided on the upper flanges of the beams 5 and receive the transversely extending planks 18 which constitute the floor of the derrick. The marginal beams 13, shown at the bottom of Fig. 1, are parted or formed in two sections, thus providing an aisle-way or entrance in the front of the structure for access-affording purposes. These marginal beams may be suitably supported by resting on columns 7 and being connected with the corner legs 14 of the associated derrick.

The structure thus far described furnishes a sufficient support for the derrick floor and the mechanism used in the operation of the well with the exception of the drilling apparatus and the casing support.

To support the drilling apparatus and the well casing, the framework indicated generally by the numeral 19 has been provided adjacent the central portion of the substructure. This framework is mounted on the piers 4 and includes a plurality of pedestal members 20 having vertically extending columns 21 provided at their lower ends with laterally extending feet 22. The upper ends of the columns 21 receive and support laterally extending I-beams 23 which, in turn, receive longitudinally extending girder members 24. The end portions of the girder members 24 rest on the I-beams 23 and are suitably secured thereto in spaced relation. To maintain this relation, a plurality of cross-shaped braces 25 are secured to inclined plates 26 carried by the webs 27 of the girders adjacent the end portions.

To prevent lateral movement of the columns 21, due to the heavy loads imposed on the girders 24, wing-like webs 28 are connected with the inner sides of the columns 21 and the feet 22. The framework thus formed is further strengthened by securing plates 29 to the feet 22 and the lower flanges of the girders 24 and connecting angle members 30 at their ends with the plates 29. By this construction a table-like support is provided for the reception of the rotary drilling apparatus and the well casing which is held by the apparatus in the operation of lowering the casing into the well bore.

It will be noted from the various figures in the drawings that the framework 19 is substantially free from engagement with the remaining portions of the substructure and may be independently removed therefrom after the drilling operations have been completed. When the framework 19 is in position adjacent the well bore, the short and demountable longitudinally extending beam sections 5a are supported thereby but after the framework or casing support 19 has been removed, suitable columns may be provided to receive the sections 5a in order that they will furnish sufficient support for the derrick floor in the vicinity of the longitudinal axis of the substructure. It will be seen that when the beam sections 5a are disconnected from the frame structure, a substantially rectangular opening is provided therein which permits of ready removal of the units of the framework or casing support 19 by lifting the same through said opening.

The casing support is capable of considerable modification such as has been illustrated in Figs. 7 and 8 wherein the laterally extending feet have been omitted and the columns 21a reenforced against lateral movement by X-bracing 31. In this form, the plates 29 and the brace 30 are also provided to increase the rigidity of the frame structure.

From the foregoing, it will be apparent that a substructure has been provided which includes a plurality of independent frame units, certain of which are constructed of relatively heavy strong parts capable of withstanding severe strains during the drilling operation. These parts are removable from the balance of the substructure and may therefore be transferred to a new location, thus decreasing the initial cost of the apparatus necessary in drilling subsequent wells. Since the support for the rotary drilling apparatus is independent of the balance of the substructure, the loads and vibratory forces incident to the drilling operation will be transmitted directly to the foundation of the derrick without passing through the corner legs and the piers on which they are supported.

While the substructure may be modified in many ways, it is desired to reserve the right to all such modifications as may be embraced within the scope of the following claims.

What is claimed is:

1. A substructure for well derricks comprising a framework having a group of relatively spaced longitudinally extending beams, a second group of relatively spaced beams arranged immediately below the beams of the first group to support the latter, the beams of the second group being disposed at right angles to the beams of the first group, the beams of the second group adjacent to the intermediate portions of the beams of the first group being in short length sections in order to terminate in spaced relation from the center of the framework to provide an elongated opening

therein, the beams of the second group arranged adjacent to the ends of the beams of the first group extending continuously and without interruption from side to side of the framework, and well casing supporting means arranged below and in vertical registration with said opening, said means being substantially unconnected with the rest of the substructure and independently removable with respect thereto.

2. A substructure for well derricks comprising a rigid framework, the latter embodying an upper group of spaced longitudinally extending beams and a second group of spaced beams arranged immediately below the beams of the first group to support the latter and extending at right angles thereto, a foundation, spaced columns arising from said foundation for effecting the support of said beams in horizontal planes, the beams forming the central regions of said second group being of shorter length than the beams comprising the outer portions of said second group, and the beams of the upper group being spaced apart at the center of the framework, whereby to form an opening in the center of said framework, and an independently mounted removable well casing supporting means mounted on said foundation below said beams and in vertical registration with said opening.

3. A substructure for well derricks comprising a foundation, a rectangular horizontally disposed frame structure consisting of a plurality of rigidly united relatively spaced longitudinally and transversely extending beams, the transversely extending beams at the central region of said frame work being of shorter length than the transverse beams forming the outer portion of said frame work, and the longitudinally extending beams being spaced apart at the center of the frame work whereby to provide in the center of the frame

work an elongated opening, spaced vertically disposed columns having their lower ends attached to said foundation and their upper ends joined with said frame work to effect the support of

5 the latter in a horizontal plane above said foundation, and a well casing supporting frame structure mounted on said foundation independently of the aforesaid frame work below and in vertical registration with said opening, the well casing

10 supporting frame structure being removable through said opening.

4. A substructure for well derricks comprising a foundation, a rectangular horizontally disposed frame structure consisting of a plurality of rigidly united relatively spaced longitudinally and transversely extending beams, the transversely extending beams at the central region of said frame work being of shorter length than the transverse beams forming the outer portion of said frame

15 work, and the longitudinally extending beams being spaced apart at the center of the frame work whereby to provide in the center of the frame work on elongated opening, spaced vertically disposed columns having their lower ends attached

20 to said foundation and their upper ends joined with said frame work to effect the support of the latter in a horizontal plane above said foundation, supplementary shorter length beams demountably joined to said outer portion of said

25 frame work and having their innermost ends spaced apart at the region of said elongated opening, and a well casing supporting frame structure mounted on said foundation independently of the aforesaid frame work below and in vertical regis-

30 tration with said opening, the well casing supporting frame structure being removable through said opening, when said supplemental beams are removed.

JOHN D. McEWEN.
